Inventor:
Joseph M. Kaye,
By George W. Chittenden & Miller,
Atty's.

UNITED STATES PATENT OFFICE

JOSEPH M. KAYE, OF CHICAGO, ILLINOIS, ASSIGNOR TO EISEMAN KAYE COMPANY,
OF CHICAGO, ILLINOIS, A CORPORATION OF ILLINOIS

CASE

Application filed March 10, 1928. Serial No. 260,679.

My invention relates more particularly to cases for receiving women's toilet articles and of the general character known as vanity cases.

5 My primary object is to provide a novel and simple construction of case of the kind above stated; to provide a case adapted to contain a large assortment of articles, particularly toilet articles; to provide a case 10 presenting a mirror portion which is housed within the case when the latter is closed and is protected against damage by contact with articles in the case, and preferably by a receptacle-forming portion of the case; and 15 other objects as will be manifest from the following description.

Referring to the accompanying drawings:—

Figure 1 is a perspective view of the case 20 showing it in open condition and with the mirror-protecting receptacle-forming portion swung to a position in which the mirror is uncovered for use; and Figure 2, a sectional view taken at the line 2—2 on 25 Fig. 1 and viewed in the direction of the arrows.

Referring to the particular illustrated embodiment of my invention the case comprises a body portion 10 open at its top 30 and preferably of the collapsible type, for receiving articles, such as for example bottles or jars of toilet preparations. To this end the body portion may be formed of a rigid rim portion 11 at its upper open end, 35 a comparatively rigid bottom forming plate-like member 12 and a connecting side wall portion 13 of flexible material.

The case also comprises a comparatively rigid plate-like cover portion 14 hingedly 40 connected along one edge to the adjacent edge of the body 10 as by a strip 15 of flexible material, the cover 14 being provided on its inner face with a mirror 16. The mirror is shown as held in place by means 45 of a relatively rigid sheet 17 which contains

an opening 18 the wall portions of which overlap the peripheral edges of the mirror, the sheet 17 being stitched along its marginal edges to the body portion of the cover 14.

50 Means such as the strips of tape represented at 19 and secured to the body 10 and the cover 14 are provided to limit the extent to which the cover is opened.

55 The case further comprises a holder element 20 which is located at the inner face of the cover 14 and is preferably hinged along one edge to the cover to permit it to be swung into and out of a position in which it covers the mirror.

60 The holder element 20 is preferably relatively thin and is shown as formed of a sheet-like body portion 21 presenting a flexible portion 22 along its upper edge which is confined between, and sewed to, the body 65 portion of the cover 14 and the sheet portion 17 thereby to form the hinged joint above referred to.

65 In the particular arrangement shown the holder element 20 is formed with pockets 70 23 and 24 at its opposite faces, the pocket portion 24 being expansive and provided with a cover flap 25 and the pocket 23 unprovided with such a flap.

75 Any suitable means are preferably provided for releasably holding the holder element 20 flatwise against the inside of the cover 14, the means shown comprising a ball and socket fastener the two cooperating parts of which are secured to the cover 14 80 and the holder element 20, respectively, the latter having a tab 26 which may be drawn upon to disengage the fastener.

85 Fastening means are also provided for releasably holding the cover in closed position these means comprising, in the particular construction shown, tabs 27 secured to the rim portion 11 of the body 10 and provided at their free ends with the socket members 90 of ball and socket fastening devices, the

ball parts of which are secured to the cover 14.

The case is preferably provided with a looped strap 28 at which it may be hung 5 on the finger of the person carrying it, this strap being preferably located at one end of the case and connected at its opposite ends with the rim portion 11 and the bottom sheet 12 of the body of the case.

10 By constructing a case in accordance with my invention the mirror carried by the cover portion thereof is kept clean and is protected against damage by contact with articles, such as bottles, jars or the like, or 15 metal articles which may be carried in the body of the case, and yet may be readily rendered accessible for use by merely swinging the holder element 20 out of mirror-covering position.

20 Furthermore, a case constructed in accordance with my invention permits of the carrying of a large assortment of articles, especially toilet articles, in a relatively compact structure.

25 The expandible feature of the body 10 is of advantage in a case of this kind, particularly when the case is provided with a carrying strap as shown and above described, as the expandible body portion expands only 30 to such an extent as is necessary to accommodate the particular articles introduced into it whereby the case presents only such bulk as is necessary to accommodate the contained articles and this is ensured by the provision 35 of the carrying loop as stated which tends to collapse the body.

What I claim as new, and desire to secure by Letters Patent, is:

1. A case comprising a receptacle-forming 40 body having an open side, a cover for said open side hinged to said body, and a holder element attached to the cover adjacent a free edge of the cover and accessible in the open position of the cover.

45 2. A case comprising a receptacle-forming body having an open side, a cover for said open side hinged to said body, and a holder element hinged at one edge to the free longitudinal edge of said cover accessible in 50 the open position of the cover.

3. A case comprising a receptacle-forming body having an open side, a cover for said open side hinged to said body, a holder element hinged to the cover adjacent a free 55 edge of the cover, and means releasably holding said element against hinge movement.

4. A case comprising a collapsible receptacle forming body portion, a flexible carrying element connected at its opposite ends with 60 the top and bottom portions of said body and means at said top and bottom portions to cause said portions to move toward each other by gravity under the weight of the contents of the case when the case is held 65 by and thus suspended from said element.

5. A case comprising a collapsible receptacle-forming body portion having an open side, said body portion being formed of relatively rigid members at the top and bottom thereof and a flexible intermediate portion, 70 a cover for the open side of said body and a flexible carrying element connected at its opposite ends with said relatively rigid members, said relatively rigid members causing the top and bottom portions of the case 75 to move toward each other by gravity under the weight of the contents of the case when the case is held by and thus suspended from said element.
